UNITED STATES PATENT OFFICE.

JAMES D. SCOVILLE, OF YORK, PENNSYLVANIA, ASSIGNOR TO S. MORGAN SMITH CO., OF YORK, PENNSYLVANIA, A CORPORATION OF PENNSYLVANIA.

DRAFT TUBE FOR HYDRAULIC TURBINES.

Application filed December 7, 1923. Serial No. 679,144.

To all whom it may concern:

Be it known that I, JAMES D. SCOVILLE, a citizen of the United States, residing at York, in the county of York and State of Pennsylvania, have invented new and useful Improvements in Draft Tubes for Hydraulic Turbines, of which the following is a specification.

This invention relates to draft tubes for either vertically or horizontally disposed hydraulic turbines. The improved draft tube is of the angular elbow type, comprising a primal tube member disposed to receive the water direct from a vertically or horizontally arranged turbine runner and opening into an angular member discharging or liberating the water into a tail race or analogous means for carrying the water away from the complete draft tube comprising the two members.

In the vertical shaft type of turbine the water is discharged from the runner vertically downward and must be turned to a horizontal direction during passage to the tail race. The water leaves the runner at a relatively high velocity, and inasmuch as this represents a considerable amount of energy, the velocity must be gradually decreased and discharged from the draft tube at a relatively low velocity, thus regaining as much as possible of the said energy of the water as it leaves the runner. Since the height that the runner may be placed above tail water is limited by the atmospheric pressure, or by the seal over the turbine required in low head installations and by the depth under tail water, because of the high cost of deep pits, it is desirable to turn the water from a vertical to a horizontal direction in a short space, and at the same time reduce the velocity to a low value.

Tests have shown that the best draft tube for all purposes is the vertical, conical type with an angular flare of about four to six degrees with a considerable depth under the mouth, to allow the water to be discharged from the draft tube without back pressure, disturbance or other avoidable losses. This type of tube must be relatively long to reduce the velocity to a low value, and inasmuch as the height which the runner may be set above tail water is limited as described above, it follows that the vertical, conical tube requires a comparatively deep pit, ex-

cept for very small turbines, and for large turbines the length of the vertical tube and depth of the pit necessary to reduce the velocity of the discharge to the usual amount becomes so great as to make the cost prohibitive. Other types of draft tubes have been designed to reduce the required depth of excavation, but they have been objectionable because they embody shapes and sections difficult and expensive to form in either concrete or metal, and usually require excessive width, thus lengthening the power house and making it difficult to provide proper foundational support for the power house. These tubes, therefore, add greatly to the cost of installation.

The usual form of elbow draft tube is not objectionable because of depth and width of excavation, or difficult and expensive foundational support, but because it is difficult and expensive to form in either concrete or metal, and it does not regain the energy of discharge of the water as it leaves the runner as completely as possible.

One of the objects of the present invention is to eliminate the objections to the different types of draft tubes above mentioned and provide a comparatively inexpensive draft tube which does not require a deep or wide pit and does not decrease the efficiency of the turbine below that obtained with the vertical, conical type of tube.

It is also known as the result of experiments that it is more efficient to allow the water to descend vertically through a passage with constantly increasing area by maintaining the center line of the passage vertical to the lowest practicable position to reduce the velocity of the water as much as possible, and then allowing the water to spread out somewhat before passing through the horizontal part of the passage into the tail race. The water in the vertical part of the passage or draft tube descends in such manner that in each sector of equal angular extent there is an approximately equal quantity of water. The velocity at the outside of the passage or tube is usually greater than at the inside, and in some turbine draft tube structures the velocity at the center may be negative or upwards, or the center may be full of voids and whirls. The water after it is spread

must be guided to the tail race by the horizontal portion of the draft tube, and this portion of the draft tube is quite important, inasmuch as a considerable amount of energy due to the velocity of the water still remains, which must be regained if the tube is to produce the maximum possible efficiency. This is done by increasing the area of the passage in a down-stream direction. 5 Thus when the water reaches the discharge end of the draft tube it flows slowly and smoothly into the tail race.

It is a further object of this invention to provide an elbow draft tube having a primal member to receive the water from the runner with an increased area at the outlet portion thereof relatively to the discharge area of the runner, and to make the enlarged extremity of the primal member on a slope at an angle of inclination, so that the water may be efficiently taken care of by the angular elbow member which serves as a guiding passage, the volume of water entering the angular elbow member serving as a guiding passage increasing from the upstream part of the primal member to the downstream part of the latter. A still further object of the invention is to utilize the enlarged upwardly sloping or inclining outlet extremity of the primal draft tube member, in cooperation with an angular elbow member serving as a guiding passage having either a level or a sloped bottom. 10 15 20 25 30 35

The disadvantages incident to draft tube constructions as heretofore proposed and practically developed do not affect the present improved form of tube. The water in the improved form of tube sometimes has a slightly whirling discharge from the receiving to the discharge extremity of the primal tube member, or at times a full or more than full revolution of the water may ensue. The sloped or inclined formation of the discharge extremity of the primal draft tube member embodying the present features of the invention operates to give a freer outlet towards the downstream side of the draft tube than towards the upstream side. This is materially advantageous in all cases, as 40 45 50 55 60 65

the water must eventually move in a downstream direction.

It will be understood that it is proposed to use the improved elbow draft tube construction in various applications, and when it is applied to a horizontally disposed turbine, the axis of the primal member extends away from the runner in a horizontal direction and the secondary or angular elbow member, which receives the water from the primal member, is substantially vertical in its disposition. The operation of the water discharged from the primal member of the improved draft tube has the same freedom of movement in a downstream direction in either application of the improved tube. 70 75 80 85 90 95 100 105 110 115 120 125 130

In the accompanying drawings various embodiments of the improved draft tube construction are illustrated for the purpose of demonstrating the practicability thereof, but it will be understood that such changes and modifications will be at all times adopted without departing from the spirit of the invention or scope of the claims appended hereto. 120 125 130

In the drawings:

Fig. 1 is a vertical section through a vertically disposed turbine and runner embodying the features of the invention;

Fig. 2 is a view similar to Fig. 1, showing a slight modification of the structure; 80

Fig. 3 is a horizontal section taken on the line 3—3, Fig. 2;

Fig. 4 is a view similar to Figs. 1 and 2, showing a further modification of the structure; 85

Fig. 5 is a horizontal section on the line 5—5, Fig. 4; and

Fig. 6 is a longitudinal vertical section, showing the features of the invention applied to a horizontally disposed turbine. 90

As shown by Figs. 1, 2 and 4 the numeral 5 designates a vertical type of turbine having an upwardly extending shaft 6, a runner 7 and suitably operated gates 8, which control the inlet of the water to the runner 7 and in practice may be supplied through the medium of a scroll case well known in hydraulic installations. In Fig. 6 the invention is applied to a horizontally disposed turbine installation 9 having a runner 10 with a horizontally extending shaft 11 and gates 12, all operating similar to the vertical turbine installations as shown by Figs. 1, 2 and 4 and differing from the latter only in a change of position. 100 105

In all of the applications of the improved draft tube two essential draft tube members or components are disclosed, namely, a primal draft tube member 14, which receives the water discharged from the runner, and an angularly disposed member 15, which in the several forms illustrated may be slightly varied and will be hereinafter specifically referred to. In the application of the invention as shown by Fig. 6 the primal draft tube member or component 16 has its axis extending in a horizontal direction and the angular draft tube member or component 17 is disposed substantially vertical, to accommodate the application of the improvement to a horizontally disposed turbine installation. 110 115 120 125 130

In all of the structures illustrated the primal draft tube member or component 14 or 16 has a similar construction in essential features and gradually diverges or increases in diameter from the receptive extremity thereof adjacent to the runner towards the discharge extremity communicating with the angular member or component 120 125 130

15 or 17, and, furthermore, the enlarged extremity of the primal draft tube member or component 14 in all of the forms shown has its enlarged extremity sloped or inclined upwardly from the upstream longer portion thereof towards the downstream shorter portion, as at 18 to 19. A slight difference in structure of the outlet extremity of the primal draft tube member or component 14 is shown by Fig. 4, the variation consisting of a slight curvature or flare, as at 20, these flaring curves, which merge into different portions of the upper walls of the angular draft tube member or component 15 into which the said primal member discharges, having radii by which they are defined materially less in length than half the diameter of the enlarged or outlet extremity of the primal member or component 14 or 20 16 of the draft tube.

In the construction of the improved elbow draft tube as shown by Figure 1, the lower enlarged upwardly sloped or inclined discharge extremity of the primal member or component 14 extends into the angular elbow member or component 15 or depends below the top wall of the latter. The angular elbow member 15 as shown by Fig. 1 is in the form of a pit having a substantially 25 horizontal straight or flat bottom 21 and a top wall 22 also substantially horizontal, the lower extremity of the primal draft tube member or component being located at a distance from the end wall 23 so as to give ample space for discharge. The level of the 30 tail water in this pit is indicated at 24^a and the direction of flow or discharge of the water from the member or component 14 into the member or component 15 is indicated by the arrows 24, 25, and 26, which are pointing downstream. The upward slope in a downstream direction of the discharge extremity of the member of the draft tube receiving the water from the runner 35 is to give more area in a downstream direction and to allow the water to be more readily discharged in a downstream direction.

In the application of the invention as shown by Fig. 2, the horizontal member or component 15 has a lower substantially horizontal straight wall 27 and a top upwardly and outwardly inclined wall 28, and the lower sloped or inclined enlarged extremity 40 of the primal member or component 14 terminates and intersects the rear terminal of the top wall 28 and also a short inclined wall 29 adjacent to the vertically reduced terminal or end wall 30 of the member 15, the short top wall 29 having the same inclination as the lower enlarged outlet extremity of the member or component 14. The distance of the short vertical end wall 30 from the lowermost maximum depending portion of the draft tube member or

component 14 permits a relief or a freer discharge of the water from the member or component 14 into the member 15 at this point, the water taking the course as indicated by the arrows in Fig. 3 in a downstream direction. 70

In the modification shown by Fig. 4 the bottom 31 of the angular elbow member or component 15 is inclined downwardly, the top wall 32 being similar to the wall 28 as 75 shown by Fig. 2, and moreover, the rear short top wall 33 is like the rear wall 29 as shown by Fig. 2. The feature of difference as hereinbefore referred to in this modified structure is the curved flared construction, as at 20, of the discharge or outlet end of the member or component 14, the lower terminal of the curved flare merging into the respective walls 32 and 33. The rear end wall 34 of the member or component 15 as shown by Fig. 4 is also vertical as in the form shown by Fig. 2. The bottom inclined wall 31 assists in the downstream flow of the water through the member or component 15 towards the tail race 80 or other means for carrying the water away from the improved draft tube structure. The course of the water in the component 15 as shown by Fig. 4 is clearly illustrated in Fig. 5 from the rear end wall in a downstream direction by the arrows. 85

The angular elbow members or components 15 as shown by Fig. 2 are restricted pit structures which cooperate with the primal draft tube member or component, 100 and the main object in view in both the substantially horizontal or level bottom structures 27 of Fig. 2 and the downwardly sloped or inclined bottom 31 of Fig. 4 is to save excavation, particularly in the case 105 of turbine installations which will not admit of a very deep pit structure. It will also be seen in Figs. 3 and 5 as illustrated by dotted lines that the side walls 35 and 36 of the angular elbow members or components 110 of the restricted pit type are outwardly converged, so as to give further deceleration of the water passing from the angular members or components 15 into the tail race or other medium of conveyance for the water. 115 It will further be seen that the level of the tail water in both forms of the improved draft tube as shown by Figs. 2 and 4 stands above the uppermost wall of the members or components 15 in these two forms as at 120 37. Also, in Figs. 2 and 3 the same direction of flow from the primal member or component 14 into the angular member or component 15 and through the latter is indicated by arrows similar to those shown by Fig. 1. 125

In the application of the improved draft tube to a horizontally arranged turbine as shown by Fig. 6, the structure is in all respects similar to that illustrated by Fig. 2, with the exception that the bottom wall of 130

the member or component 15 shown by Fig. 2 is arranged as the outer vertical wall 38 of the component 17, and the upper portion 39 of the inner side wall corresponds to the short top wall 29 in Fig. 2, and the lower portion 40 of the inner wall in Fig. 6 corresponds to the outer longer inclined top wall 28 illustrated by Fig. 2. The arrows 41, 42 and 43 also indicate in Fig. 6 the same direction of flow of the water from the member or component 16 into and through the angular member or component 17. In this connection it will be understood that the same structure as shown by Fig. 6 may be used with a pair of horizontal shaft turbines, the change only requiring a duplication of parts.

As hereinbefore indicated, the water passing through the primal member or component 14 or 16 is discharged into the angular member or component 15 or 17 with freer movement, in view of the difference of length of the primal member or component 14 or 16 on opposite sides of the central axis thereof and regularly therearound, and also the several forms of the angular members or components 15 and 17 have their rear walls at a distance from the maximum extent of the primal member or component from the runner, so as to permit the water to freely discharge in opposite directions to the sides of the angular members or components 15 and 17, to reduce the formation of eddies and confusion of the water discharged at this part of the improved draft tube structure. To save excavation and reduce cost of construction and also facilitate flow of the water downstream through the member or component 15 or 17, it is intended, as shown by Fig. 5, to eliminate the corners or angles between the side and rear walls as shown by Fig. 3 and construct these intersecting portions of the walls in curved lines or as fillets, as at 44.

In addition to the advantages of the slope or inclination of the enlarged outlet extremity of the main tube or chamber and whereby the water is facilitated in its discharge in a downstream direction, the water which may be whirling as it passes through and is discharged from the member 14 is allowed to continue its whirling movement in the elbow or angular member 15 or 17 and along the latter to the outlet thereof, or in the same plane as the said angular or elbow member 15 or 17. The sloped or inclined bottom wall 31 of the angular or elbow member 15 should not be at too great an angle, to avoid any tendency to produce confusion of the water at the back of the tube member 14.

From the foregoing description it should be understood that the improved elbow draft tube has been devised and practically operates to overcome deficiencies in draft tube constructions heretofore used and in which

water may be turned from a vertical to a horizontal flow or from a horizontal to a vertical flow in connection with a horizontally disposed turbine. The essential feature of the invention irrespective of the construction of the secondary or angular draft tube member in the several forms hereinbefore described is the main draft tube member which receives the water directly from the runner or other water-driven device of a turbine having an increased area at the outlet extremity thereof relatively to the discharge area of the runner, and to make the said enlarged discharge extremity on a slope or at an angle of inclination in a downstream direction relatively to the secondary or angularly disposed elbow member, in order to give a freer outflow from the said main or primal water-receiving element or member, and it should be further understood that it is not intended that the invention be limited to the exact angle or inclination shown, or the particular deviseinent hereinbefore explained and embodying a slope or angle of inclination, as it is proposed to utilize any other structure that will shorten the length of the main or receiving member of the draft tube in direct communication with the runner or other water operated means of the turbine at one side of the axis of the said latter member, and to dispose the shorter extent of this main member of the draft tube so that it will discharge towards the downstream direction of movement of the water in the remaining portion or member of the draft tube, with material advantages in efficiency of operation of the turbine.

What is claimed as new is:

1. An elbow draft tube comprising a primal tube member to receive the water from a turbine, and an angular member, the primal member being diverged and decreasing in length towards its discharge extremity in the downstream direction of the angular member.

2. An elbow draft tube comprising a primal member and an elbow member at an angle thereto, the primal member being diverged at its outlet extremity and gradually shortened in length from the upstream towards the downstream direction of the angular elbow member.

3. An elbow draft tube comprising a primal member to receive the water directly from a turbine, and an angular elbow member, the primal member having a diverged outlet extremity with an upward terminal slope, the outlet extremity of the primal member being freely open to the angular elbow member.

4. A water-receiving draft tube member having a discharge extremity with a forward upwardly inclined terminal.

5. A water-receiving draft tube member of an elbow draft tube regularly diverging

its full length to the outlet extremity thereof and decreasing in length from a maximum to a minimum extent at the forward downstream portion of the discharge extremity to accelerate the discharge of the water from the member.

6. A water-receiving tubular member of an elbow draft tube gradually diverging fully at its outlet extremity and decreasing 10 in length in advance of the longitudinal axis and at the downstream side portion of the member, and means at an angle to the said member and into which the latter discharges.

15. 7. In an elbow draft tube, a primal member for receiving water from a turbine gradually increasing in diameter towards its outlet extremity, the outlet extremity being inclined to gradually reduce the length of 20 the member towards one side of the longitudinal axis at the downstream side portion of the member, and means into which the member discharges.

8. An elbow draft tube comprising a 25 primal member gradually increasing in diameter fully to its discharge extremity to receive water from a turbine, the discharge extremity of said member being also disposed at an angle of inclination, and an 30 angular elbow member into which the primal member discharges, the incline of the discharge extremity of the primal member being from a lowermost point at the up-stream portion of the angular elbow member upwardly to the highest point in 35 the direction of the downstream portion of the said angular member.

9. In an elbow draft tube, a primal 40 water-receiving tubular member having a discharge extremity which is inclined and enlarged, and an angular elbow member with which the discharge extremity of the primal member has communication, the angular elbow member having a divergence 45 relatively to the discharge extremity of the said primal member.

10. An elbow draft tube comprising a 50 primal tubular member to receive water from a turbine, the said member having an enlarged extremity with an upward inclination from a maximum to a minimum extent thereof, and an angular elbow member with which the discharge extremity of the primal member has open communication, the angular elbow member having a downwardly

sloping bottom in the direction of the downstream course thereof.

11. An elbow draft tube comprising angularly intersecting members, the one member having an enlarged upwardly sloping forward portion opening into the other member.

12. An elbow draft tube consisting of a vertically disposed primal member to receive water from a turbine, the said member gradually diverging downwardly and having an upwardly sloped bottom, and an elbow member at an angle to the said vertical member, the vertical member having its greatest dependence at the upstream portion 70 of the said angular elbow member.

13. An elbow draft tube consisting of a vertically disposed primal member to receive water from a turbine, the said member gradually diverging downwardly and 75 having an upwardly sloped bottom, and an elbow member at an angle to the said vertical member, the vertical member having its greatest dependence at the upstream portion of the said angular elbow member and located at a distance from the upstream end 80 wall of the said angular elbow member.

14. The combination with a turbine having water operated means, of an elbow draft tube comprising a primal tube member diverging from the turbine and having its discharge extremity sloped at an upward angle of inclination from a maximum to a minimum extending portion thereof, and an angular elbow member with which the enlarged sloped discharge extremity of the 90 primal member has communication.

15. An elbow draft tube comprising a primal member to receive the water directly 95 from a turbine and an angular elbow member, the primal member having a diverged outlet extremity, with an upward terminal slope, the outlet extremity having a curved flared construction merging into the angular elbow member.

16. An elbow draft tube comprising a primal member to receive water directly from a turbine and an angular elbow member, the primal member having a diverged outlet extremity with an upward terminal 105 slope, and the angular elbow member also diverging in a downstream direction.

In testimony whereof I have hereunto set my hand.

JAMES D. SCOVILLE.
